MANUAL POWER SCREW PROPELLED
LIFEBOAT

Arthur P. Horn, Tampa, Fla.

Application December 5, 1950, Serial No. 199,174

2 Claims. (Cl. 115—24)

1

This invention relates to a boat, and more particularly to a manually propelled lifeboat.

This invention is an improvement on my patent on a lifeboat, No. 1,371,896.

The object of the invention is to provide a lifeboat which has an improved, manually operable means for propelling the boat.

Another object of the invention is to provide a boat which is propelled along by manually operable means that includes levers that are adapted to be worked back and forth so that the speed of the boat can be regulated, the mechanism further including movable handles that are adapted to be worked back and forth, whereby this back-and-forth movement of the handles will be converted to a rotary movement of the propeller shaft, there being a means for eliminating lost power and for preventing the flywheels from stopping in center position.

A further object of the invention is to provide a boat construction which is extremely simple and inexpensive to manufacture.

Other objects and advantages of the invention will be apparent during the course of the following description.

In the accompanying drawings forming a part of this application, and in which like numerals are used to designate like parts throughout the same:

Figure 1 is a longitudinal, vertical, sectional view taken through a lifeboat, having the propelling means of the present invention therein;

Figure 2 is a top plan view of the assembly of Figure 1;

Figure 3 is a sectional view taken on the line 3—3 of Figure 1;

Figure 4 is an end elevational view of the structure illustrated in Figure 3;

Figure 5 is a sectional view taken on the line 5—5 of Figure 4;

Figure 6 is a sectional view taken on the line 6—6 of Figure 4;

Figure 7 is an enlarged sectional view taken on the line 7—7 of Figure 5.

Referring in detail to the drawings, the numeral 1 indicates the boat in which is journaled the propeller shaft 2 which carries the propeller 3, Figure 1. The inner end of this propeller shaft is of square shape in cross-section, as shown at 4, and a number of bevel gears 5, preferably three, are slidably mounted on this square portion. These gears are provided with square holes for receiving the shaft. Each gear is provided with a grooved collar 5' with a groove 5'' and which engages the forked end of a hand lever 6, 7 and 8.

2

A suitable pivot pin 9 pivotally connects each of the levers 6, 7 and 8 to a support member 10, and the rear end of the support member 10 may be secured to the under surface of a seat 11 by suitable securing elements, such as bolt-and-nut assemblies 12.

A drive shaft 14 is arranged crosswise of the boat and this shaft 14 carries a pair of large, spaced, parallel, vertically disposed flywheels 17 and 17', Figure 4. The drive shaft 14 is rotatably supported by a pair of spaced brackets 15, and the brackets 15 may be secured to the bottom of the boat by suitable bolt-and-nut assemblies 16. Each of the flywheels 17 and 17' is provided with three rows of beveled teeth 18, 19 and 20, Figure 3, and these rows of teeth are arranged in the form of a circle. The rows of teeth 18, 19 and 20 are adapted to be engaged by the bevel gears 5 upon movement of the proper levers 6, 7 or 8. The rows of teeth 18, 19 and 20 are spaced apart so as to permit the bevel gears to be moved into and out of engagement with the teeth. As will be understood, one of the bevel gears 5 is adapted to be moved into and out of engagement with the teeth 20, while the centermost bevel gear 5 is adapted to be moved into and out of engagement with the row of teeth 19. The frontmost bevel gear 5 is adapted to be moved into and out of meshing engagement with the row of teeth 18. Thus, the propeller shaft can be driven at three different speeds or it can be entirely disconnected from the large gear wheels or flywheels 17 and 17'.

Secured to the bottom of the boat adjacent the front end thereof is a bracket 21, Figures 1 and 2, the bracket 21 being secured to the bottom of the boat by suitable securing elements, such as bolts 22. A pin 24 pivotally connects the lower end of an arm or handle 23 to the bracket 21, and a hand piece 25 is secured to the upper end of the handle 23 so that the handle 23 can be readily rocked back and forth about the pin 24. A reciprocating member 26 has its front end pivotally connected to the handle 23 by a pin 27, and the rear end of the reciprocating member 26 is pivotally connected to a handle 28 by a pin 29, Figure 1. Secured to the upper end of the handle 28 is a hand piece 30 which is adapted to be gripped so that the handle 28 can be readily rocked back and forth.

Secured to the flywheel 17 is a hub or sleeve 31 which is provided with a plurality of teeth on its outer surface. The shaft 14 extends rotatably through the sleeve 31 and through the flywheel 17. The other flywheel 17' is also provided with a sleeve or hub 32 which rotatably embraces the

shaft 14, and the sleeve 32 is also provided with a plurality of spaced teeth, as shown in Figures 4 and 6. The sleeves 31 and 32, being rotatable on the shaft 14, permit the handles 22 and 28 to be reciprocated in order to rotate the flywheels on the shaft 14.

Secured to the lower end of the handle 28 is a casing 33. Reciprocably or slidably arranged in the casing 33 is a plurality of body members 34 and 37. A pair of the body members 34 are arranged on one side of the handle 28, while the pair of body members 37 are slidably arranged in the casing 33 on the other side of the handle 28. A coil spring 35 is provided for normally urging each of the body members downwardly in the casing 33. The lower end of each of the body members 34 is provided with a tooth 36 having an inclined surface 40, Figure 5, while the lower end of each of the body members 37 is also provided with a tooth 38 having an inclined surface 41. It will be seen from Figures 5 and 6 that the teeth 36 are inclined in an opposite direction from the teeth 38. This will enable the flywheels 17 and 17' to be rotated in opposite directions when the handle 28 is rocked back and forth.

In use, the levers, 6, 7 or 8 are moved until the desired bevel gear 5 engages with one of the rows of teeth 18, 19 or 20, so that the propeller shaft 2 or propeller 3 will be turned at a desired speed. Thus, the speed of the boat can be regulated or controlled. Then the hand grips 25 and 30 are gripped by the persons propelling the boat, and the handles 23 and 28 are rocked back and forth. This causes the body members 34 and 37 to rotate either the flywheel 17 or 17', depending upon whether the handles 23 and 28 are being rocked forwardly or backwardly. Thus, there will be no lost motion and there will be no stopping in center.

By means of the previously-described construction, power will be alternately supplied to one flywheel and then to the other as the handles are rocked back and forth. These flywheels will turn in opposite directions. In other words, the movement of the handles 23 and 28 can be converted to a rotary movement of the propeller shaft 2 without the propeller 3 stopping in center position.

What is claimed is:

1. A lifeboat comprising a propeller shaft, a propeller mounted on the rear end of said shaft, a drive shaft arranged transversely on said propeller shaft, a pair of brackets secured to the bottom of the boat for supporting said drive shaft, the front end of said propeller shaft being of square cross section, a plurality of bevel gears slidably arranged on the square end of said propeller shaft, a pair of spaced parallel vertically

disposed flywheels rotatably mounted on said drive shaft, annular rows of gear teeth arranged on said flywheels to be engaged by said bevel gears, a support member secured within said boat, a plurality of levers pivotally connected to said support member and having their lower ends positioned contiguous to said bevel gears, a sleeve secured to each of said flywheels and provided with a plurality of teeth, said drive shaft extending through said sleeves, a first handle movably positioned between said flywheels, a casing secured to the lower end of said handle, and spring pressed body members having inclined teeth slidably mounted in said casing and engaging said sleeves.

2. A lifeboat comprising a propeller shaft, a propeller mounted on the rear end of said shaft, a drive shaft arranged transversely on said propeller shaft, a pair of brackets secured to the bottom of the boat for supporting said drive shaft, the front end of said propeller shaft being of square cross section, a plurality of bevel gears slidably arranged on the square end of said propeller shaft, a pair of spaced parallel vertically disposed flywheels rotatably mounted on said drive shaft, annular rows of gear teeth arranged on said flywheels to be engaged by said bevel gears, a support member secured within said boat, a plurality of levers pivotally connected to said support member and having their lower ends positioned contiguous to said bevel gears, a sleeve secured to each of said flywheels and provided with a plurality of teeth, said drive shaft extending through said sleeves, a first handle movably positioned between said flywheels, a casing secured to the lower end of said handle, and spring pressed body members having inclined teeth slidably mounted in said casing and engaging said sleeves, a reciprocating member having its rear end pivotally connected to said first handle, and a second handle pivotally connected to the front end of said reciprocating member.

ARTHUR P. HORN.
